LOCK

Emerich Deutsch, Vienna, Austria

Application February 23, 1933, Serial No. 658,159,
and in Austria July 6, 1932

2 Claims. (Cl. 70—14)

This invention relates to a lock which is designed more particularly for trunks and the like. An essential feature of this lock is that a stand-
5 ardized basic type of lock can be adapted for operation by keys of different cross-sectional shape by virtue of the arrangement that there is placed upon the inner locking mechanism proper of the lock a rotatable insert or fitting plate which is provided with an aperture correspond-
10 ing to the cross-sectional shape of the key.

The manufacturer is thus enabled to put a large number of different locks on the market with the aid of a single basic type, by simply inserting into each lock during manufacture a
15 different fitting plate adapted to the cross-sectional shape of the key to be supplied with each lock.

A form of lock in accordance with the present invention is shown, by way of example, in the
20 accompanying drawing, in which:

Fig. 1 is a front elevation.

Fig. 2 is a section taken on the line A—A of Fig. 1, with the operative portion of the key shown inserted in the lock.

25 Fig. 3 is a transverse section taken on the line B—B of Fig. 1, the key being shown in the position which it occupies after having been turned through 90° from the position in which it is shown in Fig. 2.

30 Fig. 4 shows a fitting plate with an aperture of different shape from that shown in Fig. 1.

Fig. 5 is a view of the interior of the lock in the locking position.

Fig. 6 is a similar view as Fig. 1 but with the
35 front plate removed.

Fig. 7 is a cross section on line C—C of Fig. 4.

Referring to the drawing, the fitting plate c is
40 rotatably mounted between the front plate a of the lock and the bolt b, by virtue of the arrangement that the said fitting plate is provided with a chamfered projecting or bulging portion which is adapted to fit into the aperture in the front plate of the lock, and by means of which the fitting plate is retained in contact with the front
45 plate. The fitting plate is provided with an aperture which corresponds to the cross-sectional shape of the key o. To the bolt b there is attached a knob d projecting outwards beyond the front plate of the lock, by means of which the bolt can be thrust back against the action of the
50 spring i, the head or operative end e of the bolt being thereby caused to liberate the staple or stirrup f of the hasp g.

In the locking position of the mechanism,
55 shown in Fig. 5, the bolt can not be withdrawn,

since its inwardly bent lug h bears against the tumbler-spring i.

At the same time the spring i rests by means of a step m against the stop k which projects inwards from the rear wall of the lock. On rotation of the key o the spring i is lifted over the stop k formed in the casing s by the foremost ward p of the key, and drawn towards the right until the second step n snaps into engagement with the stop k (see Fig. 1).

60 The lock according to the invention is reliable in action and gives the impression of a Yale lock with triple tumblers.

I claim:

1. In a lock, a front plate having an opening 70 therein, a key receiving member rotatably fitting in said opening and having a flange on its inner end bearing against the rear face of the front plate around said opening, and a lock bolt slidably mounted on the rear face of the front plate and 75 bearing on the rear end of the key receiving member to hold the same in place, said lock bolt having an opening to allow a key to project through the said opening in the said lock bolt when inserted in said key receiving member. 80

2. In a lock, a front plate having an opening therein, a key receiving member rotatably fitting in said opening and having a flange on its inner end bearing against the rear face of the front plate around said opening, and a lock bolt having 85 offset ends bearing on the rear face of the front plate, the portion of the lock bolt between the said offset ends bearing on the rear end of the key receiving member to hold the same in place, said lock bolt having an opening to allow a key 90 to project through the said opening in the said lock bolt when inserted in said key receiving member.

EMERICH DEUTSCH.
